UNITED STATES PATENT OFFICE.

HARRY THAYER KINGSBURY, OF KEENE, NEW HAMPSHIRE.

DESIGN FOR A TOY-CAR BODY.

SPECIFICATION forming part of Design No. 30,377, dated March 21, 1899.

Application filed January 13, 1899. Serial No. 702,109. Term of patent 14 years.

To all whom it may concern:

Be it known that I, HARRY THAYER KINGSBURY, a citizen of the United States, residing at Keene, in the county of Cheshire, State 5 of New Hampshire, have invented a certain new and original Design for a Toy-Car Body, of which the following is a description, reference being had to the accompanying drawings and to the letters and figures of reference 10 marked thereon.

My invention relates to a new and original design for a car-body; and the leading feature consists especially in the peculiar shape and configuration of the car-body hereinafter described.

The design is illustrated in the accompanying drawings, in which—

Figure 1 is a side elevation of a toy car embodying my design. Fig. 2 is an end view, 20 and Fig. 3 is a bottom plan view of the same.

In the drawings, A represents the side of

the car-body, which is shown as provided with openings 1 and has formed on its lower edge projections 2 3. The roof of the car is formed with a raised central portion B, the top of 25 which is flat and bends down at the ends, as shown at 4, and is provided with the openings 5, while from the base of the raised portion the roof is inclined downwardly to the sides, as shown at 6, and these side portions 30 have also the projecting inclined ends 7.

Having thus described my invention, what I claim, and desire to secure by Letters Patent, is—

The design for a toy-car body, substantially 35 as shown and described.

In testimony whereof I affix my signature in presence of two witnesses.

HARRY THAYER KINGSBURY.
